UNITED STATES PATENT OFFICE.

PAUL DE CARSALADE DU PONT, OF PARIS, FRANCE, ASSIGNOR OF ONE-HALF TO GABRIEL ESCARRAS, OF PARIS, FRANCE.

SYLLABLE-WRITING MACHINE.

1,024,679.

Specification of Letters Patent. Patented Apr. 30, 1912.
Application filed July 19, 1909. Serial No. 508,509.

To all whom it may concern:

Be it known that I, PAUL DE CARSALADE DU PONT, a citizen of the French Republic, and residing at Paris, France, have invented 5 certain new and useful Improvements in Syllable-Writing Machines, of which the following is a specification.

This invention relates to syllable-writing-machines, that is to say to typewriting-machines in which several characters are printed simultaneously, and it relates more particularly to a printing mechanism specially destined for this type of machines. Such printing mechanism serves for executing 10 two distinct functions, it first has to bring the different type levers to the printing point above the paper and then to print the characters in striking the paper by the types.

Referring to the accompanying drawings, 20 Figure 1 is a plan view of the mechanism; Fig. 2 is a section on line A—B of Fig. 1; Fig. 3 is a section on line C—D of Fig. 1; Fig. 4 is a section on line E—F of Fig. 1; Fig. 5 represents on a larger scale and in 25 cross section one of the key-boards, which is seen parallel with the line A—B of Fig. 1; Fig. 6 is a section on line M—N of Fig. 5; Fig. 7 is a section on line G—H of Fig. 6; Fig. 8 is a section on line I—J of Fig. 6; Fig. 9 is a section on line K—L of Fig. 6; 30 Fig. 10 is a detail illustrating in perspective view one of the type-levers.

The typewriting machine embodying my invention includes as many separate key-boards as there are characters which can be simultaneously printed; in the example shown it has been supposed that there can be printed simultaneously eight different characters and the corresponding key-boards are designated by a^1 , a^2 to a^8 . It is clear that the various key-boards do not comprise all the same number of finger-keys b .

Fig. 5 illustrates in longitudinal section 45 one of the key-boards, a^3 , Fig. 6 showing the same in horizontal section, and Figs. 7, 8 and 9 representing cross sections of said key-board. Each finger key b is rigidly connected with a rod e (Fig. 9) and all the 50 rods e of the same key-board a^3 are situated on the same vertical plane (Fig. 6); each of said rods e terminates at its lower end by an enlarged part d which has at the left hand side an indentation f and at the right 55 hand side an arm e . All the arms e bear

upon a rail g which is fixed upon a shaft h^3 parallel to said rail and adapted to be oscillated by said rail. Said shaft therefore will oscillate as soon as one of the finger-keys is struck and return to its normal position 60 if said finger-key is released, which itself is returned to its normal position by means of spring i , a spring k being provided for effecting the return of rail g and shaft h^3 . The rod e in descending further acts with 65 its indentation f upon a second rail m whereby a second shaft, n^3 , is oscillated which is arranged parallel with shaft h^3 . On the release of the finger-key b said shaft n^3 is returned to its normal position by the action 70 of a spring o which acts upon a lever p keyed upon one end of the shaft, so that the upper end of this lever comes in contact with an abutment piece q . The indentations f of the enlarged parts d of the rods e are 75 arranged so that their upper edges form together an oblique line mounting from the left to the right (Fig. 5) wherefrom results that, although the shaft h^3 oscillates immediately when a finger-key is being struck, 80 the oscillation of shaft n^3 is somewhat delayed in proportion to the position of the finger-key on the key-board, that is to say, if on the depression of the finger-key b which is situated at the left hand end of 85 the key-board the shafts h^3 and n^3 oscillate almost simultaneously, the motion of shaft n^3 is gradually delayed for every succeeding finger-key, so that for the extreme right hand end key the shaft n^3 will begin its oscillating 90 motion only when shaft h^3 has nearly completed its motion.

Upon one of the ends of shaft h^3 an angle lever r is keyed, one arm of which carries loosely a bevel pinion s (see Fig. 7) 95 while its other arm carries a roller t which is destined to act upon the rail u of the printing frame when the oscillating motion of the shaft h^3 is nearly completed. The pinion s meshes with two toothed segments 100 v and w , forming with the same a differential gear; said segments are loosely mounted upon shaft h^3 , the outer segment v being connected with shaft x^3 whose end is formed by a toothed wheel y^3 . Upon the 105 corresponding end of shaft n^3 a catch 2 is provided which is destined to engage with the teeth of segment v and to stop said segment. Upon the shaft n^3 there is further 110 fixed (see Fig. 8) opposite the segment w

a cam 3 which is adapted to bear against a blade spring 4 so as to push the nipple 5 of said spring between two adjacent teeth of segment w which is thus stopped; the 5 cam 3 pushes said nipple between the teeth of the segment w if the shaft n^3 is in normal position.

Whenever a finger-key b is depressed, the corresponding rod c will act immediately upon shaft h^3 which in revolving takes the pinion s along which rolls upon the segment w and, this segment being stopped by cam 3, communicates a revolving motion to the segment v whereby the toothed wheel y^3 is revolved until the indentation f of the rod c acts upon the rail m and causes the oscillating motion of shaft n^3 ; the cam 3 being moved away from the blade spring 4, segment w is released and 23 simultaneously the catch 2 immobilizes the segment v , whereupon the pinion s revolving upon the segment v takes along the segment w ; the movement of segment w is however not utilized in the apparatus, said 25 segment serving merely to revolve the pinion s around its axle during the first part of the movement of shaft h^3 . Thereupon, shaft h^3 continuing its oscillating motion, the roller t is lifted to come in contact with 30 frame u , the drive y^3 , not partaking in said motion. The finger-key b is released when it has reached its lowest position and the springs i, h, o bring the various parts back to their normal positions.

35 The types are mounted upon semi-circular bars 6 (Figs. 1 and 2) connected by a radial arm 7 with a tube 8 which terminates at its other end in a toothed wheel 9. There are provided as many semi-circular 40 type bars 6 as there are key-boards a_2 that is to say eight in the present case and consequently eight tubes 8 and toothed wheels 9; four of said tubes $8^1, 8^2, 8^3, 8^4$ are telescoped the one in the others and arranged 45 upon the right hand side of the machine (see Fig. 4) while the other four tubes $8^5, 8^6, 8^7, 8^8$, which are also telescoped the one in the others, are arranged upon the left hand side of the machine, the eight 50 type bars 6 being thus all arranged at the center of the machine as shown in Fig. 1. The arms 7 of the type bars are guided by means of nine circular guides 10 fixed upon an axle 11 which is parallel with the tubes 55 8 and said guide pieces are maintained at the required distance apart by means of rings which are of the same thickness as the arms 7. A screw 12 serves to immobilize all the parts. The outer guides 10 and the 60 outer type bars 6 are of slightly greater diameter than the guides and type bars situated at the center so that the outer surface formed by all the type bars corresponds to the surface of the cylinder 13 65 whereupon the paper 14 is held upon which

the characters are to be printed. This cylinder is arranged at a very small distance of the type bars so that the type bars have to be advanced for a short distance only to simultaneously press upon the paper 70 (see Fig. 3). The arm 7 divides each type bar into two equal parts, one part comprising the small letters and the other the capital letters. In normal position the arm 7 stands above the printing point (see 75 Fig. 2).

In order to bring any of the types to the printing position, a revolving motion has to be communicated to the type-bar either in one or in the other direction, said revolving motion being effected by means of eight wheels y^1, y^2-y^8 (Fig. 3). Each of said wheels meshes with a pinion $15^1, 15^2, 15^3$ which are arranged in two series, one at each side of the machine and mounted on 85 tubular axles of convenient diameter which are telescoped the one in the others and carry at their other ends pinions $16^1, 16^2, 16^3$ and 16^4 and $16^5, 16^6, 16^7, 16^8$ respectively which mesh with two series of pinions respectively $9^1, 9^2, 9^3, 9^4$, and $9^5, 9^6, 9^7, 9^8$. Each of the pinions 15 has a longitudinal slot so that it can be displaced upon its tubular axle in longitudinal direction, being connected with the same by a projecting arm, a pin or in any other suitable manner.

The various pinions are connected with a shifting mechanism which is not shown in the drawing and which is operated in any 100 suitable manner from a finger key with the object to shift the type levers so that the capital letters and signs are printed instead of the small letters. If the said finger key is depressed, the eight pinions 15 105 are simultaneously displaced so that they mesh with the opposite ends of the wheels y . Herefrom follows that the rotation of said pinions is reversed and consequently the type bars turn in the other direction as 110 before. The four tubular shafts of the pinions 15^1 to 15^4 are mounted on an axle 17 which is free at one end and fixed with its other end to the frame of the machine, the four tubular shafts of the pinions 15^5 to 115 15^8 being mounted on an axle 18 which is also fixed to the frame of the machine. Said axles 17, 18 which are situated the one in the prolongation of the other serve as pivots for the printing frame. This printing 120 frame consists of a cross bar u which is situated above the four rollers t , and of the two pivots 17 and 18, and further of the shaft 11 which serves as upper cross stay and of the eight tubular shafts 8 of the type-bars 6. Spiral springs 19 disposed at either end of the cross bar u maintain said bar in the normal position. Stops 20 serve to limit the movement of the printing frame. If 125 said frame is in its normal position there

is a small space left free between the lowest point of the type bar 6 and the paper sheet 14.

The printing operation is easy to understand. To simultaneously print a certain number of letters, the corresponding finger keys of the various key-boards *a* are depressed, all the finger-keys *b* for the letters which compose the syllable to be printed, 10 being depressed at the same time. When the descent of the finger-keys begins, the toothed wheels *y* revolve as has been hereinbefore explained, said revolving motion being transmitted by means of the pinions 15, the toothed wheels 16 and 9 to the tubular shafts 8, radial arms 7 and to the type bars 6 which thus are brought into the proper positions, so that, when at the end of the descending movement of the finger 20 keys the rollers *t* simultaneously lift the printing frame *u*, the corresponding characters are simultaneously printed upon the paper sheet 14; as soon as the finger keys are released, all the parts return to their 25 normal position, the radial arms 7 reassuming the vertical position shown in Fig. 2, the printing frame *u* being at the same time swung back by means of the springs 19 so that it rests again upon the abutments 20.

30 I claim:—

A syllable-writing machine in which for each group of keys a type sector is provided and in which the juxtaposed type sec-

tors are mounted upon revolving shafts which are independent the one of the others 35 and telescoped the one in the others, comprising in combination one driving shaft for each group of keys, an angle lever at each end of said axle, a planet pinion of a differential carried in the end of the one 40 arm of said lever and a roller mounted at the end of the other arm, a beveled pinion of the differential mounted upon the driving shaft, an auxiliary shaft mounted in alignment with the driving shaft, a second 45 pinion of the differential keyed upon said auxiliary shaft and a pinion mounted on the end of said auxiliary shaft, stops for immobilizing the two beveled pinions of the differential, an oscillating frame carrying the axles of the type sectors, means for operating said type sectors, pinions mounted upon the axle around which said frame pivots, telescopic tubes in said frame and toothed crowns mounted upon the ends of 50 said telescopic tubes and meshing with the pinion of the type sectors, substantially as described and shown and for the purpose set forth.

In witness whereof I have hereunto set 60 my hand in the presence of two witnesses.

PAUL DE CARSALADE DU PONT.
